(74) *Attorney, Agent, or Firm* — Gurr Brande & Spendlove, PLLC.; Robert Dan Spendlove

(57) **CLAIM**

The ornamental design for a window dressing, as shown and described.

DESCRIPTION

FIG. 1 is a perspective view of the top, front and right sides of a window dressing;

FIG. 2 is a plan view of the top of the window dressing illustrated in FIG. 1;

FIG. 3 is a plan view of the bottom of the window dressing illustrated in FIG. 1;

FIG. 4 is an elevation view of the front of the window dressing illustrated in FIG. 1;

FIG. 5 is an elevation view of the rear of the window dressing illustrated in FIG. 1;

FIG. 6 is an elevation view of the right side of the window dressing illustrated in FIG. 1; and,

FIG. 7 is an elevation view of the left side of the window dressing illustrated in FIG. 1.
